METHOD OF CONSTRUCTING PLATFORM SHOES

Fred J. Diamant, New York, N. Y.

Application November 29, 1945, Serial No. 631,545

1 Claim. (Cl. 12—142)

1 This invention relates to platform type shoe constructions, and more particularly to novel shoe platform constructions.

It is among the objects of the present invention to provide a novel platform for shoes having a stitching margin to which other elements of the shoe may be readily and easily secured; to provide a shoe platform construction comprising layers of material which are temporarily held together during construction of the shoe and permanently secured together in the final assembly of the shoe; to provide a shoe platform construction in which the platform can be of any desired height without any consequent weakening of the platform; to provide a novel, efficient and simple composite platform for shoes; and to provide a novel method of constructing a platform shoe.

These and other objects, advantages and novel features of the invention will be apparent from the following description and accompanying drawing. In the drawing:

Fig. 1 is a top plan view of a shoe platform constructed according to the present invention.

Fig. 2 is a side elevation view of the platform shown in Fig. 1.

Fig. 3 is a cross-sectional view showing the platform of Figs. 1 and 2 secured to a combined shoe upper, platform cover and sock lining.

Fig. 4 is a longitudinal sectional view through a shoe incorporating the platform of Figs. 1 and 2.

Fig. 5 is a plan view of a shoe platform embodying a modified form of the invention.

Fig. 6 is a side elevation view of the platform shown in Fig. 5.

Figs. 7, 8 and 9 are side elevation views of further embodiments of the invention.

Fig. 10 is a sectional view illustrating the platform of Figs. 5 and 6 as secured to a combined shoe upper, platform cover and sock lining.

Fig. 11 is a sectional view illustrating the platform of Figs. 5 and 6 as embodied in a shoe construction.

According to the present invention, a shoe platform of a composite nature is provided with a stitching margin to which the sock lining, the upper and the platform cover may be attached as a unit. The platform comprises a layer of cushioning material, such as felt or sponge rubber, in juxtaposition with a layer of reinforcing material such as paper-board. The stitching

2 margin is provided either by making the upper layer of the platform narrower than the lower layer or by routing out a margin around the edge of the composite platform.

5 In a modified form of the invention, the cushioning layer is secured to the reinforcing layer temporarily by suitable means such as nails, staples or the like, after which it is incorporated with the shoe upper. The stitching securing the 10 shoe upper to the platform serves the additional function of securing the two layers of the platform in assembled relation. If the platform is provided with a stitching margin, the two layers may be either temporarily secured together by 15 staples or nails and permanently secured together by the shoe stitching, or the two layers may be initially cemented together.

Platforms of any desired thickness may be provided by suitably combining alternate layers of 20 reinforcing material and cushioning material, or by combining several layers of cushioning material with several layers of reinforcing material. Alternatively, the cushioning layer may occupy 15 substantially all the height of the platform and have a single relatively thin layer of reinforcing material secured thereto.

The invention avoids the need of cementing the platform to the shoe insole or sock lining or for accurately spotting the insole and platform. 30 Due to such simplification, the shoe may be constructed by less skilled labor and at less expense. The provision of the reinforcing layer secured to the cushioning layer enables the shoe to be put over a last without deformation of the cushioning layer as would occur were no reinforcing provided therefor. The resultant shoe is less stiff since no cement is used to fasten the platform to the insole, and the foot can "breathe" through the insole due to the lack of cement. The upper 35 and the platform are combined in one single unit by a single series of stitches.

As a result, a lightweight shoe having great flexibility is provided which is more comfortable to wear and cheaper to make. With the stitching margin provided, the folded over portion of the shoe platform cover and of the shoe upper and sock lining lie substantially within the peripheral outline of the platform making the shoe appear less bulky and of less width than the usual 45 shoe of this type. The shoe construction is par-

ticularly advantageous in open heel or toe shoes in that the exposed part of the shoe retains its neat, clean looking, sharp edged appearance.

Referring to the drawings, Figs. 1 through 4 illustrate a shoe platform 15 comprising an upper layer 16 of cushioning material, such as felt or sponge rubber, and a lower layer of reinforcing or stiffening material 17, such as fiber-board, paper-board, cardboard, leather or the like. In a manner to be described, layers 16 and 17 may either be simply superposed one on the other without being secured together, or may be permanently secured together by cement. Alternatively, the two layers may be united by suitable means such as nails, stapling or the like, and then secured as a unit with the remainder of the shoe during the shoe construction operation.

In the embodiment of the invention shown in Fig. 1, layer 16 is made narrower than layer 17 to provide a stitching margin 18 for receiving the lower stitching margin 21 of upper 20 and the stitching margin 22 of platform cover 25. Such stitching margin may be provided either by initially making layer 16 smaller than layer 17 or by making both layers the same size as by stamping platform 15 from a large sheet of composite material, and then routing out a portion of layer to provide stitching margin 18.

In assembling the shoe, upper 20, sock lining 26, and platform cover 25 are initially secured together in the relation shown in Fig. 3 by stitching 23. Stitching margins 19, 21 and 22 are then placed in stitching recess 18 and are secured to reinforcing layer 17 of platform 15 by stitching 24. Stitching 24 may be done by a machine making a loop chain stitch through the several stitching margins and layer 17. No cement need be used between layer 17, sock lining 26, upper 20 and platform cover 25.

To complete the shoe, a heel member 27 may be mounted adjacent the rear portion of layer 17, as shown in Fig. 4, and platform cover 25 is reversed on itself and its lower margin 28 is secured beneath heel 27 and beneath layer 17. An outer sole 30 is then secured to the lower margin 28 of platform cover 25 in any suitable manner, and a lift 31 is secured to the shoe in the usual manner.

Due to the fact that adhesive is not used to secure the platform 16, 17 to the insole of sock lining 26, a shoe of greater flexibility is provided. Also, as hereinabove referred to, the foot can breathe therethrough. Additionally, the platform, its cover, the shoe upper and the sock lining form a unitary construction secured together by stitching 24, increasing the life and stability of the shoe.

Figs. 5 and 6 illustrate a modified form of the invention in which a layer of cushioning material 36 is temporarily secured to a layer of reinforcing material 37 by suitable means such as staples 38 to form a platform 35. Staples 38 form temporary securing means for layers 36 and 37. The two layers are permanently secured together, and in unitary relation with the shoe upper and platform cover, in a manner to be described in connection with Figs. 9 and 10.

A further important feature of my present invention is shown in Figs. 7, 8 and 9 wherein the platform is made in any desired thickness, while still retaining its cushioning effect as well as its dimensional stability. In Fig. 7, alternate layers of cushioning material 36 and of reinforcing material 37 are secured together, such as by staples 38, to form a thick platform 40. Cushioning

layers 36 may be any suitable cushioning material such as matted fiber, sponge rubber or the like, and reinforcing layers 37 may be any suitable relatively stiff material such as cardboard, fiber-board, leather or the like.

Fig. 8 illustrates a thick platform 45 comprising two layers of cushioning material 36 secured in juxtaposition with each other and with a reinforcing layer 37 by means of staples 38. In Fig. 9, a platform 50 is provided by a relatively thick layer of cushioning material 41 secured to a relatively thin layer of reinforcing material 42. Cushioning material 41 makes up most of the height of platform 50 and is retained in dimensional stability by reinforcing layer 42 to which it is secured by staples 43.

Preferably, the peripheral edges of the felt cushioning layers are coated with animal glue or the like. The glue stiffens the peripheral edges, which reinforces the platform so that it is more stable and keeps its peripheral shape better during handling and assembling in a shoe. The glue is preferably applied after the peripheral shape of the cushioning layers has been determined, and preferably after such layers have been incorporated into a platform assembly.

Figs. 10 and 11 illustrate how platforms of the type shown in Figs. 5 through 9 may be incorporated into a shoe. For exemplary purposes only, the platform 35 of Figs. 5 and 6 is used as an illustration. In so assembling the shoe, upper 55 is secured to platform cover 60 and insole or sock lining 62 by stitching 56. The stitching margins 57, 58 and 59 of upper 55, platform cover 60 and sock lining 62 are then secured to platform 35 by stitching 61. Stitching 61 likewise permanently unites layer 36 to reinforcing layer 37.

Platform 60 is then reversed around itself and its lower margin 63 is bent beneath reinforcing layer 37 of platform 35 to which it may be secured in any desired manner. An outer sole 64 is then secured to margin 63 of platform cover 60 to complete the shoe. During the assembling operation, upper 55 may be stretched to shape over a last so that it will attain its final shape, which it retains, without deformation of platform 35. This is due to the fact that platform 35 includes a reinforcing layer 37. Furthermore, the platform comprises an integral part of the shoe assembly to which it is united by stitching 61. The same construction shown in Figs. 10 and 11 can be used with the platforms shown in Figs. 7, 8 and 9.

A lightweight shoe of great flexibility is thus provided, comprising a reinforced cushioning platform forming an integral part of the completed shoe and which retains its shape during manufacture of the shoe thus permitting the upper of the shoe to be shaped over a last to attain a preset shape. When stitching margin 18 is provided as in Figs. 1 through 4, the upper and the platform cover lie within the peripheral outline of the shoe platform providing a neat, clean appearing shoe.

While specific embodiments of the invention have been shown and described in detail to illustrate the application of the principles thereof, it will be understood that the invention may be otherwise embodied, without departing from such principles.

What is claimed is:

A method of constructing a platform shoe comprising uniting a layer of cushioning material to a layer of reinforcing material to provide a plat-

form, the upper layer having its periphery inward of the periphery of the lower layer to provide a stitching recess, juxtaposing the stitching margins of an upper, and a sock lining and a platform cover, previously secured together as a unit, in outwardly projecting relation into such stitching recess and stitching such margins and the platform together to unite said layers to said upper and said cover to form a composite assembly.
